COMBINATION CRIB AND PLAYPEN

Frederick F. Hatton, Shreveport, La., assignor to
 The Hatton-Pardue Corporation, Shreveport,
 La., a corporation of Louisiana

Application June 19, 1950, Serial No. 168,961

4 Claims. (Cl. 5—99)

1

The present invention relates to new and useful improvements in combination cribs and play pens, and more particularly to a folding device of this character.

An important object of the present invention is to provide a combination crib and play pen having rigid ends and foldable sides, the sides being composed of a pair of foldable sections whereby the sides may be folded inwardly in a compact form parallel to the ends.

Another object of the invention is to provide a foldable platform supported on foldable sides which are also hinged to the ends for folding inwardly together with the sides of the crib, the platform supporting a mattress which is removable so that the platform may then be used as the floor of the play pen.

A further object of the invention is to provide a hinged gate at one side of the crib to facilitate the placing of a child therein.

A still further object is to provide supporting brackets of a novel construction for the platform when in its lowered position.

An additional object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side-elevational view;

Figure 2 is a top plan view showing the combined crib and play pen in open position;

Figure 3 is a similar view showing the platform folded upwardly against the end and with the sides of the crib partly folded;

Figure 4 is a similar view showing the device in its completely folded position;

Figure 5 is a sectional view of the lower portion of the combined crib and play pen taken on a line 5—5 of Figure 2;

Figure 6 is an enlarged fragmentary vertical sectional view taken on a line 6—6 of Figure 2 and showing the latch for the gate;

Figure 7 is a transverse sectional view taken on a line 7—7 of Figure 6; and

Figure 8 is an enlarged fragmentary sectional view of one of the supporting brackets for the platform, taken on the line 8—8 of Figure 5.

Referring now to the drawings in detail, where-

2

in, for the purposes of illustration, I have disclosed the preferred embodiment of the invention, the numerals 5 and 6 designate the ends of the combined crib and play pen provided with corner posts 7 and the sides of the combined crib and play pen are designated generally at 8 and 9.

The side 8 is composed of a pair of foldable sections 10 and 11 connected to each other by conventional hinge structures 12 for folding inwardly one upon the other while the outer end of section 10 is connected to an adjacent corner post by conventional hinge structures 13 for folding against the end 6 and the outer end 15 of section 11 is connected by conventional hinge structures 14 to the edge of an upright 15 secured to an adjacent post and aligned with the sections 10 and 11 when the latter are in open position, as shown in Figure 2 of the drawings.

Side 9 of the combined crib and play pen is composed of a hinged section 16 and a gate 17, the gate being hinged to the section 16 adjacent the center of the crib by conventional hinge structures 18. Section 16 is hinged by conventional hinge structure to an upright 19 which is secured to an adjacent post, the upright 19 being aligned with the side 9 when in open position.

The free edge of gate 17 is provided with a vertically sliding catch designated generally at 21 and comprising a vertical metal strap 22 having vertical slots 23 therein engaged behind the heads of screws 24 secured to the end frame member 25 of the gate on the inside of the latter. Upper and lower locking bolts 26 are secured to plate 22 for movement therewith in openings 27 in the vertical frame member 25 of gate 17. The ends of the bolts are formed with downwardly extending detents 28 received in eyes 29 formed on brackets 30 which are attached to an upright vertical strip 31 supported on and adjacent post 7 by conventional hinge structures 32. The upper end of plate 22 is formed with a finger grip 21a to facilitate its raising and lowering movement.

The side 9, composed of hinged section 16, gate 17, and upright 31, is foldable inwardly toward end 5 parallel thereto and also parallel to the folded side 8 and end 6, as shown in Figure 4, the uprights 15 and 19 at opposite corners of the crib spacing each folded side from one end to accommodate the other folded side in parallelism with each other and with the ends.

A combined mattress support for the crib and floor for the play pen comprises a pair of plat-

form sections 33 and 34 hinged to rails 35 and 36 mortised in the posts 7 of each end 5 and 6 for swinging the platform sections upwardly against the adjacent end.

The platform sections are supported in a lowered horizontal position on duplicate side frames 37 and 38 each composed of hinged sections 39 and 40 hinged connected to each other by hinges 41 and with section 39 hinged to a corner post 7 by hinges 42 and section 40 hinged to an adjacent upright 15 or 19 by hinges 43 similar to the adjacent side of the crib 8 or 9.

Supporting brackets 44 are secured to the side frames 37 and 38 and have upstanding tongues 45 received in recesses 46 in the under side of the platform sections.

In the operation of the device, when the sides 8 and 9 are swung into an open position parallel with each other, as shown in Fig. 2, the sides are locked from collapsing movement by swinging platform sections 33 and 34 downwardly to rest on brackets 44 which lock the platform to supporting frames 38 and 39.

Gate 17 may be opened by releasing latch 21 and swinging the gate outwardly, whereupon a child may be placed in the crib, either on a mattress (not shown) supported on platform sections 33 and 34, or directly on the platform, which serves as the floor of a play pen.

When the device is not in use, platform sections 33 and 34 are swung upwardly against the ends 5 and 6 and sides 8 and 9 collapsed inwardly at the hinges 12 and 13, in the manner shown in Figure 3, against the ends 5 and 6 to position the folded sections of the sides parallel to the ends, as shown in Figure 4. The platform supporting frames 38 and 39 collapse with the sides 8 and 9.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A crib comprising corner posts having a pair of end structures fixed thereto, an upright at one side of each of a pair of diagonally opposite posts and projecting inwardly with respect to the adjacent end structure, each of a pair of foldable side structures hingedly connected at one end to said uprights, at least one of said side structures including a gate having a free end and a hinged end, a vertically slideable member carried by the free end of the gate, a bolt carried by said member for vertical movement therewith, a vertical strip hinged to an adjacent post, and an

eye carried by the strip and adapted to lockably receive the bolt.

5 2. A crib comprising corner posts and side and end structures, said side structures being hinged to the posts for folding movement, at least one of said structures including a gate having a free end and a hinged end, and means locking the free end of the gate to an adjacent post and including a vertically sliding member carried by the gate, a bolt carried by said sliding member, and an eye on the post adapted to receive the bolt.

10 3. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

15 4. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

20 5. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

25 6. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

30 7. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

35 8. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

40 9. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

45 10. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.

50 11. A crib including corner posts having a pair of end structures fixed thereto, an upright at one side of each of a pair of diagonally opposite posts and projecting inwardly with respect to the adjacent end structure, each of a pair of foldable side structures hingedly connected at one end to said uprights, a vertical strip hingedly secured to one of the remaining corner posts, one of said side structures including a gate having a free end and a hinged end, the free end of said gate terminating adjacent said vertical strip, a vertically slideable member carried by the free end of said gate, a bolt carried by said member for vertical movement therewith, a bracket having an eye therein secured to said vertical strip and adapted to lockably receive said bolt.
